GEORGE T. BENTON, OF WILLOW SPRINGS, MISSOURI, ASSIGNOR OF ONE-HALF TO
OTTIS A. McDILL, OF WILLOW SPRINGS, MISSOURI.

DOUBLE CLAMP.

1,352,647.

Specification of Letters Patent. Patented Sept. 14, 1920.

Application filed May 21, 1920. Serial No. 383,161.

To all whom it may concern:

Be it known that I, GEORGE T. BENTON, a citizen of the United States, and a resident of Willow Springs, in the county of 5 Howell and State of Missouri, have invented certain new and useful Improvements in Double Clamps, of which the following is a specification.

My present invention relates generally to 10 clamping devices, and more particularly to a double clamp which may be utilized for various purposes in connection with the fitting and setting of doors, windows and the like, my object being the provision of a simple effective double clamp of a jointed nature which will facilitate certain specific operations in addition to its more general application in other uses.

In the accompanying drawing illustrating 20 my present invention,

Figure 1 is a sectional side view illustrating the practical application of my invention,

Fig. 2 is an edge view,

Fig. 3 is a sectional view through one of 25 the clamping members taken on line 3—3 of Fig. 1,

Fig. 4 is a detail perspective view of one 30 of the clamping frames,

Fig. 5 is a detail perspective view of a portion of the other frame, and

Fig. 6 is a detail perspective view of one 35 of the clamping levers.

Referring now to these figures, each of 40 the clamping members or devices includes a U-shaped clamping frame 10, one terminal of which has a laterally elongated bearing piece 11 and through the other terminal of which is threaded a clamping screw 12 preferably having a swiveled clamping piece 13 at its inner end opposing the bearing plate or piece 11 and having an adjusting lever 14 pivoted to its outer end. The two clamping frames 10 have shanks 15 and 16 projecting therefrom and provided with openings 17 and 18 the latter of which is threaded so that the shank ends may be con-

nected in overlapping relation and pivoted to one another by a pivot pin 19 in the form of a thumb screw. The shank 15 has ribs 50 20 arranged at diametrically opposite sides of its opening 17 and the shank 16 has a series of recesses 21 radiating from its opening 18 and into selected recesses of which the ribs 20 may be extended so that by 55 tightening the pivot forming thumb screw 19, the shanks 15 and 16 may be adjustably secured in desired angular relationship.

Thus by means of the clamp, the opposite clamping members of which are engageable with a stationary portion indicated at A in Fig. 1 and a movable part indicated at B, the movable part may be held in desired relation to the stationary part while certain operations are proceeded with as for 60 instance the planing of a door or window in fitting the same within its receiving frame, or for instance when setting the hinges of a door, although it is understood that the invention is not limited to this use and in fact 65 may be utilized for various purposes in connecting movable objects to stationary objects where the size of the movable object, to be planed, grooved or otherwise operated upon, is too large in size for clamping in a 70 bench vise, and it is to be understood that my invention contemplates a clamp of this nature as applied in general use to any and 75 all purposes for which it may be adapted.

I claim:

80 A sectional clamp, each section including an outer U-shaped frame having a bearing member at one side and an adjustable clamping element through its opposite side opposing the said bearing member, and a 85 shank at the outer end of which the frame is disposed, the inner ends of the two shanks being pivoted in overlapping relation and having relatively engaging ribs and recesses around their pivot, and a clamping wing 90 bolt forming the pivot between the shanks whereby the two sections may be readily adjusted and rigidly held.

GEO. T. BENTON.
